APPARATUS FOR CONTROLLING PRESSURE

Robert R. McIntosh, Battle Creek, Mich.

Application October 12, 1942, Serial No. 461,665

16 Claims. (Cl. 236—45)

1

The present invention relates broadly to draft regulation, and in its specific phases it relates more particularly to methods and apparatus for use in connection with the regulation of induced draft pressures in railway locomotive smoke boxes.

Railway locomotives for a long period of time have utilized exhaust steam from the driving cylinders for creating induced draft. The creation of that induced draft is accomplished in the locomotive smoke box by directing at least a portion of the exhaust steam from locomotive cylinders out through the locomotive smoke stack to produce a siphon effect. This siphon effect in turn reduces the pressure in the smoke box and produces induced draft which is transmitted through the fire tubes to the fire box of the locomotive. In order to moderately compress and lower the range of suction pressures created in this manner, it has been standard practice to install baffles, partition plates, and netting in the smoke box, and to place a long ignition arch in the fire box. The extent to which this procedure can be carried is limited due to its adverse effect on the lower ranges of suction pressures. The higher suction pressures produced in this manner under normal operating conditions not only reduce the combustion efficiency of the locomotive but also interfere with the uniform burning of the fire bed. The superheater units, stay bolt heads, smoke stack, smoke stack extension, and other front end parts which come in contact with the products of combustion which carry an excessive amount of abrasive material, due to the pulsating high velocity flow caused by the conventional induced draft generation, are rapidly worn out by abrasive action. Two ways of improving the drafting of a railway locomotive in manner overcoming or at least substantially reducing the prior difficulties in this field, have been set forth in my U. S. Patents No. 2,379,916, granted July 10, 1945, and No. 2,377,895, granted June 12, 1945. These two patents deal with multiple suction pressure level draft regulation through the use of a plurality of separate air inlet valves in the smoke box. The operation of those inlet valves is suitably controlled in accordance with predetermined settings based on the drafting demands of the locomotive, or manually if desired. My present invention involves the modification, simplification, and improvement of the aforementioned inventions wherein the use of multiple dampers are eliminated.

Accordingly among the objects of the present invention is the provision of a single damper mechanism which is adapted to control the upper

2

suction levels in the locomotive smoke box at a plurality of points which are prechosen to meet the induced draft requirements.

Another object is to provide an apparatus for controlling a single inlet damper in manner permitting same to open at different prescribed suction pressure levels.

A further object is to provide a single draft control damper, which is supplied with a weighting system which adds or removes weight from said damper in accordance with changes to be made in draft suction pressure levels.

A further object is to provide automatic control, manual control, or both types of control in connection with the control of suction pressure levels in a locomotive smoke box by means of a single damper mechanism.

A still further object is to provide a single damper mechanism for regulating locomotive drafting in manner permitting the elimination of all or a substantial portion of the baffles, partitions, netting, etc., in the locomotive front end.

Still further objects and advantages of the present invention will appear as the description proceeds.

To the accomplishment of the foregoing and related ends, the invention, then, consists of the means hereinafter fully described and particularly pointed out in the claims, the annexed drawings and the following description setting forth in detail certain means for carrying out the invention, such disclosed means illustrating, however, but several of the various ways in which the principle of the invention may be used.

35. In said annexed drawings:

Figure 1 shows a side elevation of a locomotive front end embodying the present invention.

Figure 2 is a partially sectioned, diagrammatic, elevational view taken along line 2—2 of Figure 1, 40 and with manual as well as one form of automatic control mechanism shown in enlarged size and in connected position.

Figure 3 is an elevational view of the cam and valve assembly, on reduced scale, looking in the 45 direction of the arrows along line 3—3 of Figure 2.

Figure 4 is a top view of the cam assembly looking in the direction of the arrows along line 4—4 of Figure 3.

50. Figure 5 is a partially sectioned elevational assembly of one form of valve particularly adapted for use as shown in Figures 2 and 3.

Figure 6 is an enlarged and partially sectioned central elevational assembly of a preferred form 55 of the present invention.

Figure 7 is a plan view as taken along line 7—7 of Figure 6 looking in the direction of the arrows, but with the dome-like cover removed and certain parts broken away for clarity of illustration.

Figure 8 is a plan view of the weights and weight lifting forks as taken along line 8—8 of Figure 6 looking in the direction of the arrows, but with parts broken away for clarity of illustration.

Figure 9 shows a diagrammatic arrangement for controlling the suction pressure levels of an oil fired locomotive.

Figure 10 shows a diagrammatic arrangement for electrically controlling the suction pressure levels of a locomotive.

Referring more particularly to Figures 1 and 2 of the drawings, the locomotive 1 has a smoke box 2 with conventional door 3 at its front end for use in inspecting or repairing the various parts mounted within the smoke box or accessible therethrough. An exhaust stand 4 with nozzle 5 is connected in conventional manner to the exhaust outlet from the driving cylinders (not shown). Directly above the exhaust stand is a smoke stack which has a flared bottom 6 which is commonly referred to as a petticoat. The delivery of the exhaust steam from the nozzle of the exhaust stand through and sealing the inside of the smoke stack creates suction in the locomotive smoke box when the locomotive is under motion. The suction pressures thus produced in the smoke box are transmitted through the locomotive fire tubes (not shown) to the fire box (not shown) to facilitate combustion of fuel in the latter. A blower ring 7, conventionally connected for delivery of live steam up the smoke stack, is utilized for creating a light suction pressure when the locomotive is standing, drifting, or otherwise requires a slight increase in draft.

Mounted in the upper portion of the smoke box between the smoke stack and door 3 is a tubular member 8, which, for simplicity of removal, is preferably flanged at both ends and conventionally joined to flanged end tubular members 9 and 10 which in turn are welded or otherwise suitably joined in substantially air-tight manner to shell 11 of smoke box 2. This smoke box shell is cut away at the outer ends of tubular members 9 and 10 to provide free access of air through these tubular members into tubular member 8. In order to permit ready closing of the inlet ends of tubular members 9 and 10, sliding doors 12 and 13 are provided and these in turn are held in place and guided in their endwise movement by means of ways 14 and 15. Tubular members 8, 9, and 10 may be of various cross-sectional contours although one of the most simple forms of same involves the use of a flat top rectangular section. Tube 8 for instance, may have a suitable opening 16 (Figure 6), or the equivalent, in the flat top of same for a purpose to be hereinafter described in detail. The upper face of tubular member 8, at opening 16, may be provided with a ring 17 suitably welded or otherwise fastened thereto and faced to form a valve seat. Mounted directly above tubular member 8 is a valve assembly which will now be described in detail.

The closing of opening 16 in tubular member 8 is accomplished by means of a valve disc 18 mounted on shaft 19 in conventional manner, for instance by means of collars 20 and 21, which, if desired, may be welded both to shaft 19 and valve disc 18. The sealing of valve disc 18 on ring 17 may be accomplished in various ways, and one of the most convenient involves the use of a

gasket 22 formed from a woven strip of asbestos packing which is approximately $1\frac{1}{4}''$ x $\frac{1}{4}''$ in section and riveted on or at 2" centers to the under face of disc 18 in the area which lies over valve seat ring 17. The latter may be provided with a groove 23 directly below the rivet circle of the gasket to provide a clearance for same as well as a better seal under operating conditions.

Depending into the upper portion of the locomotive smoke box 2, directly above valve disc 18, is a pan 24. This pan may be joined in substantially air tight manner to the locomotive smoke box by various means, for instance by welding, or the like. A preferred construction involves the

use of a flanged ring 103 which is anchored to smoke box shell 11 by welding, riveting, or the like. The joining of pan 24 to this ring by means of bolts, studs, or cap screws, makes the assembly readily removable for repairs, et cetera. The upper edge of pan 24 is preferably flanged outward to facilitate fastening to ring 103. This flange 25 is also adapted to have mounted thereon a suitable hood member 26 with flange 27 adapted to be joined in conventional manner to flange 25 of pan 24. Where there is ample room ahead of the smoke stack, pan 24 may be made with a circular top. Sometimes, however, attachments to a locomotive front end ahead of the smoke stack limit the available space and in that case pan 24 may be made narrow lengthwise and long crosswise of the locomotive smoke box to fit the available space.

Under operating conditions, it has been found that valve disc 18 tends to spin and thus cause unnecessary wear. This may be avoided by various constructions, and one of the most simple ways of doing so consists of anchoring one or more guide rods 28 on the upper face of valve disc 18 near the outer edge thereof, and providing inverted cups 29 in corresponding location within pan 24. The raising and lowering of valve disc 18, under these conditions, merely causes guide rods 28 to move up and down in cups 29 of pan 24 thus preventing rotation of the valve

disc. The guide rods in this case are made a little longer than the actual clearance space between the top of valve disc 18 and the bottom face of pan 24 to insure that rotation will be completely avoided.

Mounted on pan 24 is a carrier plate 30 which may be partially cut away as shown in Figure 6 for purpose of lightening the assembly. A pillow block bearing 31 suitably joined to carrier plate 30 acts to guide the upper end of shaft 19 in its up and down movement. This pillow block bearing may be of either the oilless or greased type. The lower end of shaft 19 is guided by means of a bearing 32 which may be of either the greased or oilless type and which in turn is mounted on a supporting member 33 which extends across tubular member 8 and is anchored at both ends thereto. Shaft 19 is provided with an enlargement 34 which may be either a unit part of shaft 19, or a collar conventionally fastened thereto, and the showing in Figure 6 is intended to diagrammatically cover these various forms of construction.

The bottom of pan 24, at the point where shaft 19 passes therethrough, is provided with an opening 35 of sufficient size for enlargement 34 to freely pass therethrough. A closure member 36 is preferably mounted directly above opening 35, and for convenience this closure member may be of the split and pivoted type commonly used with annular openings.

Valve disc 18 which is exposed on its upper face to suction pressures within the smoke box, and at its under face to atmospheric pressures in tubular member 8, may be made of such an assembled weight and size that when weights 37 and 38 are in elevated position, the exceeding of a predetermined minimum suction pressure in the smoke box will cause valve disc 18 to move upward from its seat and permit the ingress of air from tubular member 8 into the smoke box 10 to restrict the suction pressure therein substantially to the predetermined minimum. When a predetermined higher suction pressure is to be permitted in the smoke box, then weight 38 may be lowered to the position shown in Figure 6 so that it rests on enlargement 34 of shaft 19 whereupon the disc valve assembly is increased in weight to the extent of the weight thus added, and the suction pressure necessary to lift same is greater.

If a still higher suction pressure is to be permitted in the smoke box, then weight 37 may be lowered to the position shown in Figure 6 so that same is added along with weight 38 to that of the assembly including valve disc 18. The use of two weights with a suitable operating mechanism thus makes possible the controlling of the draft suction pressures in the smoke box substantially at 3 different levels. This invention, it is to be understood, is not limited to the use of two weights and 3 levels, but rather to one or more weights and two or more levels since such variations do not depart from the spirit of the present invention. For convenience of illustration, weights 37 and 38 have been shown in lowered position, although under actual operating conditions they may be normally either at upper or lower positions. The mechanism for raising and lowering weights 37 and 38 will now be described.

Mounted on carrier plate 30 are a pair of cylinders 39 and 40. Cylinder 39 is conventionally provided with upper and lower headers 41 and 42 which are flanged and joined to carrier plate 30 by means of studs 43 which also pass through a shimming block 44 (Figure 7). Passing through lower header 42 is a piston rod 45, the upper end of which carries piston 46 while the lower end of same is fastened to lower fork member 47. The fork end of this fork member is adapted to pass under radial flange 48 of weight 38 and clear same slightly when piston 46 is in its lowermost position as shown in Figure 6. In order to make a smoother operating combination, lower fork member 47 is counterbalanced by means of a weighted end 49 which substantially balances weight 38 about the center line of piston rod 45. As a means of guiding fork member 47 at all times, weight member 49 is preferably provided with substantially flat sides 50 and 51, which in actual operation, slide up and down guide ribs 52 and 53 which are conventionally joined to pan 24.

In similar manner, cylinder 40 is provided with upper and lower headers 54 and 55, which are fastened by means of studs 56, and shimming block 57 to carrier plate 30. Piston rod 58 extends through lower header 55 and has piston 59 mounted on its upper end. The lower end of piston rod 58 is fastened to upper fork member 60. The fork end of this fork member is adapted to engage the underface of radial flange 61 on upper weight 37 for raising and lowering same. The fork end of upper fork 60 in this case, along with weight 37, is made radially larger so that

lower fork 47 and weight 38 can pass upward without interfering with the fork end of upper fork 60 even though same remains in its lowermost position. In order to balance the upper fork 60 when it is lifting weight 37, the counter weighted end 62 of this fork is preferably provided with substantially flat sides 63 and 64 which, in actual operation, slide up and down guide ribs 65 and 66 conventionally joined to pan 24.

Where a fluid pressure system is utilized for the raising and lowering of weights 37 and 38, the lower ends of cylinders 39 and 40 may be connected to a suitable source of low pressure gaseous fluid such as air or steam, such pressure being sufficient to normally hold pistons 46 and 59 in their uppermost positions with weights 37 and 38 elevated. Then when it is desired to lower one of the weights, for instance weight 38, it is only necessary to deliver a suitable higher pressure gaseous fluid to the upper end of cylinder 39 to drive piston 46 to its lowermost position. This will cause weight 38 to rest on enlargement 34 of shaft 19 and thus increase the weight of the valve assembly so that the suction pressure in the smoke box will have to raise to a higher level before disc valve 18 will raise to permit air to flow from tubular member 8 into smoke box 2. The apparatus will then substantially hold that suction pressure as the maximum over a considerable range of operation within the capacity of the valve. If it is desired to further increase this suction pressure, then a gaseous fluid at suitable pressure may be delivered to the upper end of cylinder 40 to force piston 59 to its lowermost position, whereupon weight 37 will be added to the valve assembly weight including weight 38. The elevating of the valve disc assembly under these conditions merely carries weights 37 and 38 in an up and down path while fork members 47 and 60 remain in fixed lowermost position.

Various ways of operating the present suction pressure controlling apparatus may be utilized without varying from the principles of the present invention. For instance, it may be decided to control the suction pressure level in accordance with the rate of fuel feed, or in accordance with the percentage of cut-off, or manually, or even by combinations of these or other prechosen control factors. For simplicity of understanding the operation of the invention, same will now be described in terms of automatic control in step with prescribed variations of cutoff settings. For purposes of description, but without being limited thereto, let us assume that three suction pressure levels in the smoke box are desired and that these are respectively $5\frac{3}{4}$ ", $5\frac{1}{4}$ ", and $4\frac{3}{4}$ " of water. Under these conditions, with weights 37 and 38 held in elevated position to permit free up and down movement of the assembly including disc valve 18, the weight of the latter may be so proportioned that it will start to elevate and admit atmospheric air into the smoke box when the suction pressure therein reaches and starts to exceed $4\frac{3}{4}$ " of water. Weight 38, in that case, will be made of such a size that when lowered and left resting on enlargement 34 of shaft 19, it will increase the total weight of the valve assembly to a point where same will start to open at a suction pressure of $5\frac{1}{4}$ " of water. The lowering of a suitable size weight 37, and the addition of same to the combined weight of the valve disc assembly plus weight 38 should prevent the valve assembly from opening until a suction pressure of $5\frac{3}{4}$ " of water has been reached in the smoke box. Under these conditions, the lifting

of weight 37 by means of fork 60 and the associated mechanism will automatically return the suction pressure level to the intermediate one, and then upon lifting weight 38, that in turn will automatically return the suction pressure level to the lowest one. It is thus obvious that all that is necessary to the functioning of the system is the raising and lowering of weights 37 and 38 in accordance with draft level change requirements.

The controlling of the raising and lowering of weights 37 and 38 to vary the maximum suction pressure in the smoke box between prescribed low, intermediate, and high suction pressure levels, through the actuation of the cut-off mechanism, may be accomplished in various ways, and one of the most convenient will now be described. The reverse arm 67 of the locomotive has a link 68 (Figure 3) which is suitably connected to the valve gear which actuates the main steam valve (not shown) of one of the driving cylinders so as to control the cut-off of steam admitted thereto. Reverse arm 67 is mounted on and keyed to a cross shaft 69, and on the other end of this cross shaft is mounted and keyed to another reverse arm (not shown) for operating a like cut-off control of the main steam valve for the driving cylinder on the opposite side of the locomotive. The operation of reverse arm 67 mounted on shaft 69 is therefore in accordance with the movement of the cut-off setting controls in the locomotive cab (not shown). The increasing of the per cent cut-off under forward travel of the locomotive results in reverse arm 67 being moved in clockwise direction as viewed in Figure 3. To take advantage of this for controlling the air inlet assembly, a plate 70 with arcuate flange 71 may be anchored to the side of reverse arm 67 in conventional manner, for instance, by means of screws 72. Under these conditions, the arc of flange 71 is set so that its center is approximately on the center line of cross shaft 69. Flange 71 is provided with slots 73 (Figure 4) through which extend studs or cap screws 74 which in turn are fastened to cam shoe members 75 and 76. Assembling the cam shoes on arcuate flange 71 in this manner permits adjustment of the shoes to contact and operate valves 77 and 78 at various cut-off settings, and hence govern the points of shifting of the suction pressure levels in the smoke box.

Mounted on the frame 79 (Figure 3) of the locomotive is an anchor bracket 121 on which are mounted valves 77 and 78. Rollers 80 and 81 of these two valves are adapted to engage cam shoe members 75 and 76. For instance, cam shoe 75 may be adjusted to engage and depress roller 80 of valve 77 at a cut-off setting of thirty per cent. This engagement will connect the high pressure main air line 82 through valve 77 to air line 83 which connects with the top of cylinder 39. The flow of high pressure air then forces piston 46 in cylinder 39 to its lowermost position which in turn deposits weight 38 in contact with the upper face of enlargement 34 on shaft 19. This predetermined amount of weight added to the weight of the valve assembly automatically shifts the suction pressure level at which the apparatus operates from $4\frac{3}{4}$ " to $5\frac{1}{4}$ " of water. Cam shoe member 76, for instance, in turn may be adjusted so as to engage and depress roller 81 of valve 78 at a cut-off setting of forty per cent so that under those conditions, main air line 82 will be connected through valve 78 and air line 84 to the upper end of cylinder 40. The flow of high pressure air in this circuit will in

turn force piston 59 to its lowermost position and deposit weight 37 on the top of weight 38 which is resting on the upper face of enlargement 34 of shaft 19. This predetermined amount of weight added to the weight of the valve assembly automatically shifts the suction pressure level control from $5\frac{1}{4}$ " to $5\frac{3}{4}$ " of water. In other words, when weights 37 and 38 are in their uppermost position, the apparatus will restrict the maximum suction pressure to the lowermost pressure level up to a cut-off setting of thirty per cent at which point weight 38 is lowered to raise the maximum suction pressure level to the intermediate one. Then as the cut-off is further increased, the assembly maintains this intermediate suction pressure until the cut-off setting reaches forty per cent, at which time weight 37 is lowered to raise the maximum suction pressure level to the highest one which is to be maintained. This pressure is maintained until the cut-off setting is either again raised above the forty per cent or lowered below thirty per cent, the latter, through the operation of valve 78 automatically reduces the suction pressure to the intermediate level which is maintained until the cut-off setting is either again raised above the forty per cent or lowered below thirty per cent, the latter, through the operation of valve 77, resulting in a shift to the lower suction pressure level once more. It is to be understood that the specific cut-off percentages noted are used as illustrative of the operation of this apparatus, and are not to be considered as a limitation on the invention since obviously other cut-off settings may be used so long as the principles herein set forth are utilized.

Where the gaseous fluid which is used for moving pistons 46 and 59 in cylinders 39 and 40 respectively is in the form of air, the main air line 82 which, for instance, may carry air at approximately one hundred and ten pounds per square inch, is connected through pressure reducer 85 to low pressure lines 86 and 87, the former of which leads to the lower end of cylinder 40. Low pressure air line 87 connects pressure reducing valve 85 to the lower end of cylinder 39. When either piston 46 or 59 is moved downward, due to the supply of high pressure air to the upper end of cylinders 39 and 40 respectively, this causes a back flow and building up of low pressure air in lines 86 and 87. In order to relieve this back pressure, a pressure relief valve 88 is provided. Where air pressure reducing valve 85 is set to deliver air at thirty pounds per square inch gauge, the pressure relief valve 88 may be set to relieve air in lines 86 and 87 when the pressure therein reaches or tends to exceed a prechosen pressure, for instance thirty-five pounds per square inch gauge. This moderately higher setting of the pressure relief valve outlet pressure as contrasted with the pressure reducing valve outlet pressure causes the trapped air to cushion the return movement of pistons 46 and 59 to the upper end of their respective cylinders.

Valves 77 and 78 are preferably identical in construction, and for simplicity of understanding same, one of these valves, namely valve 78, has been shown diagrammatically in partial center section in Figure 5. Referring more particularly to that figure, the movement of arcuate cam 76 (Figure 2) into contact with and over roller 81 will move push rod 90 downward under the cushioning influence of spring 91 carried by depressor arm 89 pivotally mounted on supporting member 99 by means of pivot pin 100. This downward movement in turn will depress spring pro-

jected ball bearing 92 and allow fluid to flow under pressure from compartment 93 into cavity 94 and hence out through pipe 84 to the upper end of cylinder 40. The depressing of push rod 90 at the same time moves check valve 95 downward to close the lower end of compartment 96 and substantially prevent leakage therethrough. When arcuate cam member 76 is moved out of contact with roller 81, push rod 90, under the influence of spring projected ball bearing 92 moves upward and the outlet from compartment 93 is sealed by ball 92. At the same time check valve 95 moves upward to the position shown in Figure 5, and this allows fluid in air line 84 to flow backward into compartment 94 and thence through compartment 96 and a small vent opening 97 to the atmosphere to permit release of the piston rod assembly which has been held with the piston at lowermost position due to the air pressure delivered through air line 84. Vent opening 97 and the connections leading thereto may be made relatively small, if desired, so that they will not seriously interfere with the simultaneous operation of the suction pressure level control either manually, or other than by the cam operated system just described. The placing of a valve 98 (Figure 2) which may be of conventional type, such as a needle valve, gate valve, globe valve, or the like, in the main air pressure line 82 ahead of cam operated valves 77 and 78 will make possible the shutting off of air to valves 77 and 78, and the completely independent operation of the pressure level control cylinders by manual control, or other extraneous control means.

The pressure levels may be manually controlled if desired. For instance, by opening valve 101 (Figure 2), high pressure air from main air line 82 will be delivered directly to the upper end of cylinder 39 with the result that weight 38 (Figure 6) will be lowered into contact with enlargement 34 thus shifting the upper pressure level to be maintained in the smoke box from the lower level to the intermediate level. Then by opening valve 102 (Figure 2), high pressure air will be delivered from main air line 82 to the top of cylinder 40 which in turn will lower weight 37 (Figure 6) into contact with the upper face of weight 38 and thus raise the upper suction pressure level to be maintained in the smoke box to the high level. The return of the system to intermediate and then low pressure levels is accomplished by first closing valve 102 and then valve 101. It is perfectly possible to control the apparatus manually with valve 98 either open or closed, although the latter would prevent the cam operated system from operating in conjunction with the manual control. The supplemental use of manual control presents the advantage of giving the locomotive engineer or fireman an opportunity to raise the suction pressure level manually from low or intermediate to a high level if the suction pressure for some reason is not quite high enough and the cut-off setting not sufficiently advanced to shift the suction pressure under operating conditions to the desired higher level.

The air piping and control system for normally holding weights 37 and 38 in uppermost position and the lowering of same by means of the application of suitably high pressure above pistons 45 and 59 of cylinders 39 and 40 has already been described. The invention, however, is not limited to that procedure, and an alternative procedure will now be described in connection with the controlling of an oil fired locomotive. Referring

more particularly to Figure 9, high pressure air line 82 is connected through pressure reducing valve 85 to the upper end of cylinders 39 and 40 by means of pipes 87 and 88 respectively. The application of this pressure will normally force piston rods 45 and 58 downward and hold them down so that weights 38 and 37 (Figure 6) will be in their lowermost position when valves 104 and 105 are closed. The fuel oil supply line 106 would be connected by means of valve 107 to feed pipe 108 for delivery of oil to burner 109 in the locomotive fire box (not shown). The operation of valve 107 may be controlled in conventional manner by means of an operating lever 110. This operating lever, for instance, might be provided with an extension 111 pivotally connected to an operating link 112 which in turn would be pivotally connected to valves 104 and 105 by means of operating arms 113 and 114. When the fuel oil being delivered to burner 109 is of relatively small quantity flow, valves 104 and 105 would be open and as a result weights 37 and 38 would be held in their uppermost position. Under these conditions when the fuel feed is increased to a prescribed point by the manipulation of operating lever 110, the movement of link 112 will automatically move operating arm 113 to a point where valve 104 is closed. This automatically permits piston rod 45 to move downward and deposit weight 38 on enlargement 34 of shaft 19, thus increasing the weight of the valve assembly and transferring the upper limits of the suction pressure in the smoke box to the intermediate level. A still further increase in fuel feed due to the movement of operating lever 110 would, at a prechosen point, close valve 105 through the actuation of operating arm 114. This in turn would lower weight 37 onto the top of weight 38 and thus increase the maximum suction pressure in the smoke box to the upper level. Reverse movement of operating lever 110 would first open valve 105 to elevate weight 37, and then open valve 104 to elevate weight 38, thus progressively shifting the suction pressure levels in the smoke box from high to intermediate and then to low. Connecting cylinders 39 and 40 in this manner presents the advantage of dropping weights 37 and 38 whenever anything goes wrong with the air pressure system. The dropping of these weights automatically increases the induced draft suction pressure level, a thing which would be important since it would permit maximum draft for the locomotive and take care of peak operating conditions even though the air system for operating valves 39 and 40 was out of order. Pressure relief valve 88 set at a somewhat higher pressure than pressure reducing valve 85 would preferably be used as before described. Valves 104 and 105 in preferred construction would be provided with a bleeding outlet on the cylinder side of same so that when these valves are closed, the air pressure in the corresponding pipes 83 and 84 would be gradually relieved to permit the ready functioning of the system.

The operation of the system through the agency of air or steam pressure provides feasible means of control of the damper system due to the presence of steam and compressed air on the locomotive. The invention, however, is not limited to that type of control, since the latter may be of electrical nature. Referring, for instance, to Figure 10, the system may be electrically connected to a suitable source of electric power. This system utilizes solenoids 39a and 40a electrically connected to the main line through cam

actuated switches 115 and 116. Rods 45a and 58a in this case would not only carry fork members 47 and 60 (Figure 6) on the lower end of same but preferably would extend up completely through solenoids 39a and 40a and have compression springs 117 and 118 respectively mounted on the upper end of each. These springs would preferably be of a size suitable to hold forks 47 and 60, as well as weights 38 and 37, in elevated position under normal operating conditions with no electricity supplied to solenoids 39a and 40a. Cam shoes 75 and 76 mounted on arcuate flange 71 would, in this case be arranged so that switch 115 would close first and deliver electricity through solenoid 39a which would be so-connected in the system as to force rod 45a substantially to its lowermost position against the resistance of spring 117. This operation of solenoid 39a would automatically lower weight 38 onto enlargement 34 of shaft 19 and due to this added weight, it would move the upper suction pressure level from low to intermediate. Still further movement of reverse arm 67 to increase the cut-off would actuate switch 116 at a prescribed point, and this in turn would electrically force rod 58a and weight 37 downward until the latter rests on weight 38, thus raising the upper suction pressure level in the smoke box from intermediate to high. Moving reverse arm 67 in the opposite direction would, at the prescribed settings, automatically actuate switches 116 and 115 to reverse the process just described and return the system from high to intermediate and then to low upper suction pressure level. The actual setting of cam shoes 75 and 76 under these conditions would be in accordance with cut-off settings which have been prechosen to vary the suction pressures as has been described in detail above. Manually operated electrical switches 119 and 120 may be mounted in the locomotive cab (not shown), or at any other convenient point on the locomotive, and the actuation of solenoids 39a and 40a directly controlled through the operation of same. Switches 119 and 120 thus provide for manual control of the system, while switches 115 and 116 provide for automatic control of the system at predetermined points through the cut-off settings of the locomotive gear. The operation of the system in this manner has been described by way of illustration of the principles involved, and same is not to be considered as a limitation on the scope of the invention.

The electrical system shown in Figure 10, and described in detail above, is adapted for varied operation. For instance, springs 117 and 118 may be omitted, and this in turn will allow rods 45a and 58a to normally extend down with fork members 47 and 60 (Figure 6) in lowermost position and weights 38 and 37 resting on collar 34 of shaft 19. Cam shoes 76 and 75 in this case would be adjusted to close the electrical circuits through switches 115 and 116 when predetermined upper suction pressure levels below the maximum are to be maintained. For example if the suction pressure is to be held from exceeding a predetermined low suction pressure when the cut off is below 30%, then at all cut-off settings below 30% switches 115 and 116 would be held closed by cam shoes 76 and 75 respectively. The electrical circuits in this case would be connected so that the solenoids 39a and 40a would exert a lifting force to elevate forks 47 and 60 with weights 38 and 37 whenever switches 115 and 116 were closed. If on the other hand the

suction pressure is to be held from exceeding a predetermined intermediate suction pressure when the cut-off setting is between 30% and 40%, then cam shoes 75 and 76 would be so adjusted that only switch 116 would be closed in this range. The closing of switch 116 would cause weight 37 (Figure 6) to be elevated while weight 38 would be left in lowermost position where it would increase the valve and valve shaft assembly weight as previously described. Connecting the electrical system in this manner presents the advantage that in case the supply of electricity fails, the upper suction pressure level will be continuously effective so as to take care of maximum combustion requirements at all times.

While the description of the present invention has set forth in the examples in terms of using two or three suction pressure levels, it is to be understood that the invention is not limited to that but rather the principle involved is the controlling of the suction pressure at two or more levels. The air inlet valve, and the parts which cooperate therewith in accordance with the principles of the present invention, must also be of a sufficient size and capacity to substantially control the upper suction pressure to be maintained at any time in accordance with the pre-chosen pressure level requirements as varied by the mechanism for controlling the shifting of same.

Other modes of applying the principle of my invention may be employed instead of those explained, change being made as regards the means herein disclosed, provided those stated by any of the following claims or their equivalent be employed.

I therefore particularly point out and distinctly claim as my invention:

1. In a pressure reducing apparatus, the combination of a hollow member, an inlet means having a substantially horizontal opening into said hollow member, a valve for said opening, said valve being mounted to control fluid flow from said inlet means into said hollow member, means for controlling the movement of said valve in a substantially vertical direction to and from the upper side of said opening, loading means for said valve, and means for adding and removing said loading means from said valve.

2. In a pressure reducing apparatus, the combination of a hollow member, an inlet means having a substantially horizontal opening into said hollow member, a valve for said opening, said valve being mounted to control fluid flow from said inlet means into said hollow member, means for controlling the movement of said valve in a substantially vertical direction to and from the upper side of said opening, a plurality of weights, and means for engaging said weights for the lowering and lifting of same to and from the upper side of said valve.

3. In a pressure reducing apparatus, the combination of a hollow member, an inlet means having a substantially horizontal opening into said hollow member, a valve for said opening, said valve being mounted to control fluid flow from said inlet means into said hollow member, means for controlling the movement of said valve in a substantially vertical direction to and from the upper side of said opening, a plurality of weights, means for engaging said weights for the lowering and lifting of same to and from the upper side of said valve, and means for controlling the operation of said weight lifting means.

4. In a pressure controlling apparatus, the combination of a compartment wherein pressure is to be controlled, an inlet means with upper face, said inlet means having a substantially horizontal opening in its upper face, a valve for said opening, means for guiding said valve in a substantially vertical direction to and from the upper side of said opening, a plurality of weights, a plurality of means for individually engaging said weights for the raising and lowering of same, separate means for operating said individual weight engaging means, and means for controlling the operation of said individual weight engaging means.

5. In a pressure controlling apparatus, the combination of a compartment wherein pressure is to be controlled, an inlet means with upper face, said inlet means having a substantially horizontal opening in its upper face, a valve for said opening, means for guiding said valve in a substantially vertical direction to and from the upper side of said opening, a plurality of weights, a plurality of means for individually engaging said weights for the raising and lowering of same, separate means for operating said individual weight engaging means, and means for controlling the operation of said individual weight engaging means.

6. In a pressure controlling apparatus, the combination of a compartment wherein pressure is to be controlled, an inlet means with upper face, said inlet means having a substantially horizontal opening in its upper face, a valve for said opening, means for guiding said valve in a substantially vertical direction to and from the upper side of said opening, a plurality of weights, a plurality of means for individually engaging said weights for the raising and lowering of same, separate means for operating said individual weight engaging means, and at least manual means for controlling the operation of said individual weight engaging means.

7. In a pressure controlling apparatus, the combination of a compartment wherein pressure is to be controlled, an inlet means with upper face, said inlet means having a substantially horizontal opening in its upper face, a valve for said opening, means for guiding said valve in a substantially vertical direction to and from the upper side of said opening, a plurality of weights, a plurality of means for individually engaging said weights for the raising and lowering of same, separate means for operating said individual weight engaging means, and electrically operated means for controlling the movement of said individual weight engaging means.

8. In a pressure controlling apparatus, the combination of a compartment wherein pressure is to be controlled, a tubular inlet member, said inlet member having an upwardly directed opening into said compartment, a disc valve for said opening, means for carrying said valve to and from said opening for respectively sealing and opening same, a plurality of separate weights, a fork means for each of said weights, means for moving said fork means to and from said valve, whereby same may be used to add and remove one or more of said weights from said disc valve, and means for controlling the movement of said fork means.

9. In a pressure controlling apparatus for a locomotive smoke box, the combination of means for creating suction pressure in said smoke box in excess of the maximum required, a tubular inlet member, said inlet member having an up-

wardly directed opening into said smoke box, a disc valve for opening and closing said opening, a shaft on which said disc valve is radially mounted, means for guiding said shaft in endwise direction in manner such that said disc valve will be movable to and from said opening for respectively sealing and opening same, a plurality of separate weights, a fork means for each of said weights, means for moving said fork means to and from said valve whereby same may be used to add or remove one or more of said weights from said valve and shaft assembly, a shaft means on which said forks are mounted for separate movement, a counterweight for each of said forks, guide means for said counterweighted forks, a cylinder for each of said shaft and fork assemblies, a piston in each of said cylinders, each of said pistons being mounted on the upper end of said fork carrying shafts, fluid conduits connected to the opposite ends of each of said cylinders, and means for controlling the supply of fluid under pressure to said cylinders, whereby said pistons will be moved therein and weights added to or removed from the valve and shaft assembly in accordance with prescribed variations in the maximum suction pressure to be permitted in said smoke box.

10. In a pressure controlling apparatus for a locomotive smoke box, the combination of means for creating suction pressure in said smoke box in excess of the maximum required, a tubular inlet member, said inlet member having an upwardly directed opening into said smoke box, a disc valve for opening and closing said opening, a shaft on which said disc valve is radially mounted, means for guiding said shaft in endwise direction in manner such that said disc valve will be movable to and from said opening for respectively sealing and opening same, a plurality of separate weights, a fork means for each of said weights, means for moving said fork means to and from said valve, whereby same may be used to add or remove one or more of said weights from said valve and shaft assembly, shaft means on which said forks are mounted for separate movement, a counterweight for each of said forks, guide means for said counterweighted forks, a solenoid for each of said shaft and fork assemblies, the end of the shaft of each of said shaft and fork assemblies extending into operable relation with the corresponding solenoid, suitable electric connections to said solenoids, and means for controlling the supply of electricity to said solenoids, whereby said shaft and fork assemblies will be moved and weights added or removed from the valve and valve shaft assembly in accordance with prescribed variations in the maximum suction pressure to be permitted in said smoke box.

11. In a pressure regulating apparatus, the combination of an inlet means with opening therein, an endwise movable valve assembly for said opening, means for axially guiding the valve of said valve assembly positively to and from said opening, at least one valve loading weight, means for physically adding and removing said weight to accomplish self loading and self unloading of said valve assembly in manner producing at least two operating inlet pressure levels at which said valve assembly will open, and means for controlling the loading and unloading of said valve assembly in accordance with prechosen conditions.

12. In a pressure regulating apparatus, the combination of a hollow member, an inlet means having a substantially horizontal opening into

said hollow member, a valve assembly for said opening, said valve assembly being mounted to control fluid flow from said inlet means into said hollow member, means for axially guiding the valve of said valve assembly positively to and from said opening, and self loading means for mechanically adding and removing at least two load members separately from said valve assembly in manner self controlling at multiple operating levels the pressure necessary to open said valve assembly.

13. An apparatus for controlling suction pressure in a compartment, which comprises an inlet with a valve assembly adjustable so as to open and admit into said compartment through said inlet a controlled amount of suction reducing gaseous fluid when the suction pressure therein reaches a predetermined level, means for mechanically loading said adjusted valve assembly so as to increase the suction pressure level at which said valve assembly will open to admit a controlled amount of gaseous fluid through said inlet into said compartment, means for additionally loading said valve assembly mechanically so as to raise its opening suction pressure level still higher, said loading means being also adapted for mechanically removing said loading when the suction pressure at which the valve assembly opens is to be returned to a lower level, and means for controlling the actuation of said loading means so as to operably load and unload said valve assembly.

14. An apparatus for controlling suction pressure in a compartment, which comprises means for creating a suction pressure in said compartment, said suction pressure being adapted to rise above the maximum desired unless controlled, an inlet with a valve assembly adjustable so as to open and admit into said compartment through said inlet a controlled amount of suction reducing gaseous fluid when the suction pressure therein reaches a predetermined level, means for mechanically loading said adjusted valve assembly so as to increase the suction pressure level at which said valve assembly will open to admit a controlled amount of gaseous fluid through said inlet into said compartment, means for additionally loading said valve assembly mechanically so as to raise its opening suction pressure level still higher, said loading means being also adapted for mechanically removing said loading when the suction pressure at which the valve assembly opens is to be returned to a lower level, and means for controlling the actuation of said loading means so as to operably load and unload said valve assembly.

15. An apparatus for controlling suction pressure in a compartment, which comprises an inlet with a valve assembly adjustable so as to open and admit into said compartment through said inlet a controlled amount of suction reducing gas-

eous fluid when the suction pressure therein reaches a predetermined level, means for mechanically loading said adjusted valve assembly so as to increase the suction pressure level at which said valve assembly will open to admit a controlled amount of gaseous fluid through said inlet into said compartment, means for additionally loading said valve assembly mechanically so as to raise its opening suction pressure level still higher, said loading means also being adapted for mechanically removing said last applied load and then the first applied load to return the suction pressure successively in steps to the initial suction pressure level, and means for controlling the actuation of said loading means to both load and unload the valve assembly in operable sequence.

16. An apparatus for controlling suction pressure in a compartment, which comprises means for creating a suction pressure in said compartment, said suction pressure being adapted to rise above the maximum desired unless controlled, an inlet with a valve assembly adjustable so as to open and admit into said compartment through said inlet a controlled amount of suction reducing gaseous fluid when the suction pressure therein reaches a predetermined level, means for mechanically loading said adjusted valve assembly so as to increase the suction pressure level at which said valve assembly will open to admit a controlled amount of gaseous fluid through said inlet into said compartment, means for additionally loading said valve assembly mechanically so as to raise its opening suction pressure level still higher, said loading means also being adapted for mechanically removing said last applied load and then the first applied load to return the suction pressure successively in steps to the initial suction pressure level, and means for controlling the actuation of said loading means to both load and unload the valve assembly in operable sequence, whereby the maximum suction pressure in said compartment may be controlled within the capacity of the apparatus at any one of three different pressure levels.
